Primary Examiner — Philip S Hyder*Assistant Examiner* — Keith Frank(74) *Attorney, Agent, or Firm* — Colin P. Cahoon; Carstens & Cahoon, LLP(57) **CLAIM**

The ornamental design for a snack tray, as shown and described.

DESCRIPTION

FIG. 1 is a top perspective view of the snack tray; FIG. 2 is a left side view in elevation of the snack tray; FIG. 3 is a right side view in elevation of the snack tray; FIG. 4 is a front view in elevation of the snack tray; FIG. 5 is a back view in elevation of the snack tray; FIG. 6 is a top view of the snack tray; FIG. 7 is a bottom view of the snack tray; and, FIG. 8 is a bottom perspective view of the snack tray. The broken lines showing a flange is for the purpose of illustrating portions of the article and forms no part of the claimed design.
